(21) Appl. No.: **29/170,254**

The ornamental design for a continuous passive motion device for a shoulder or elbow, as shown.

(22) Filed: **Nov. 1, 2002**

DESCRIPTION

(51) LOC (7) Cl. **21-02**

The article is a continuous passive motion device used for rehabilitative treatment of a shoulder or elbow by providing range of motion exercise to the involved joint of a patient. FIG. 1 is a front perspective view of a continuous passive motion device for a shoulder or elbow showing my design; FIG. 2 is a front elevational view thereof;

(52) U.S. Cl. **D21/662**; D21/686

FIG. 3 is a rear elevational view thereof;

(58) Field of Search D21/662, 677,

FIG. 4 is a side elevational view thereof;

D21/684, 686, 691; D24/188; 482/91, 92,
133, 135, 136, 137; 601/33

FIG. 5 is an opposite side elevational view thereof;

(56) **References Cited**

FIG. 6 is a top plan view thereof; and,

U.S. PATENT DOCUMENTS

FIG. 7 is a bottom plan view thereof.
